SOCKET FOR TUBE LAMPS

Arthur Osterloo, Kansas City, Mo.

Application August 31, 1940, Serial No. 355,053

10 Claims. (Cl. 173—328)

This invention relates to electric sockets, particularly for tube lamps, and has for its principal object to provide a socket of this character which is of simple, strong construction, and not subject to breakage incidental to application of the lamp.

Other objects of the invention are to provide a socket structure which facilitates application and removal of the lamp; to provide for floating support of the socket terminals by a resilient pad whereby the socket terminals automatically adjust themselves to the prongs of the lamp; and to provide a socket that effects positive electrical contact with the lamp prongs.

In accomplishing these and other objects of the invention, I have provided improved details of structure, the preferred form of which is illustrated in the accompanying drawing, wherein:

Fig. 1 is a longitudinal section through a tube lamp lighting fixture equipped with sockets constructed in accordance with the present invention and showing the method of inserting the tube lamp.

Fig. 2 is a horizontal section through one of the sockets on the line 2—2 of Fig. 1.

Fig. 3 is a cross-section through the lamp fixture showing one of the sockets in elevation.

Fig. 4 is a perspective view of the socket terminal carrying block.

Fig. 5 is a detail perspective view of the parts of a disassembled socket and the end of a tube lamp.

Fig. 6 is a longitudinal section through one of the terminal screws.

Referring more in detail to the drawing:

1 designates a light fixture for tube lamps and may include a substantially trough-like reflector 2 enclosed in an outer shell 3. Mounted in the respective ends of the reflector are sockets 4 and 5 embodying the features of the present invention. The sockets 4 and 5 support a conventional type tube lamp 6, having prongs 7 and 8 at the respective ends thereof cooperating with contact elements of the sockets in supporting the lamp and forming a connection with a source of electrical current supply. Each socket unit includes a casing 9 and a contact carrying block 10, floatingly mounted on a resilient element 11.

The casing 9 is preferably formed of metal and includes a back 12, sides 13—14 and a bottom 15. The sides 13 and 14, including the bottom 15, are preferably formed by bending a blank sheet laterally from the portion thereof forming the back 12. The front edges of the sides 13 and

14 are provided with flanges 16 and 17 bent inwardly thereof a sufficient distance so that the edges 18 and 19 form the sides of a front opening 20. The bottom 15 is provided with a substantially rectangular shaped notch 21, opening from the front edge 22. The upper ends of the flanges 16 and 17 are provided with ears 23 and 24 forming stops as later described. The upper ends of the side walls are preferably bent laterally to provide attaching ears 25 and 26 which are adapted to engage against the reflector and to be retained thereagainst by prongs 27 and 28 struck from the reflector material, however, the attaching ears may be extended laterally and provided with openings for any suitable type of fastening device. The back 12 preferably extends above the sides and is provided with a central notch 29. The upper end of the casing is open to permit insertion of the inner parts 20 of the socket including the members 10 and 11, above referred to.

The member 10 preferably includes a block formed of insulating material, such as hard rubber, or one of the synthetic plastics, which may be suitable for the purpose. The block includes a base portion 30 having parallel side faces 31 and 32 slidably engaging the inner faces of the sides 13 and 14 of the casing and having a substantially flat back face 33. The block also includes a front portion 34 projecting from the base portion and having side faces 35 and 36 inset from the side faces 31 and 32 a distance substantially corresponding to the width of the flanges 16 and 17 of the casing so that the portion 34 is adapted to project freely through the opening 20. The front portion 34 has an upper end 37 inset downwardly from the upper end 38 of the base portion to form a stop adapted to be engaged by the ears 23 and 24 to prevent upward dislodgment of the member 10 through the open top of the casing. Extending from the longitudinal median point of the block is a finger 39, having a rounded portion 40 adapted to be engaged by the thumb for pressing the lower portion 45 of the block inwardly of the casing while the upper portion rocks relatively to the ears 23 and 24, as later described.

Formed in the projecting portion of the block, on the respective sides of the finger 39, are slots 50 41 and 42 having bottoms 43 sloping from the base portion to the front face of the projecting portion and in registry with socket terminals or contact elements 44 and 45. One of the contact elements 44—45 is best illustrated in Fig. 6, and includes a screw-like member having a threaded

shank 46 threadedly engaged in threaded openings 47 in the block and having heads 48 adapted to seat within the counterbores 49 formed in the rear face of the block. The counterbores are intersected by parallel grooves 50 and 51 in which conductors 52 and 53 are extended and bared ends thereof are engaged under the heads 48 of the contact elements, as clearly shown in Fig. 1. The shanks of the screws are of sufficient length so that the end faces 54 thereof register with the front face 34 of the block and are in a position to engage the prongs of the lamp. Formed within the shank of each screw is a tapering bore or socket 55 for receiving the prongs 7 or 8 so that an electrical contact is made thereby with the lamp. The rear face of the block is backed by a sheet of insulating material 56 which bears against the resilient bed 11.

In the illustrated instance, the bed 11 includes a substantially rectangular body of sponge rubber having a size to closely engage within the casing and of a thickness to provide the necessary pressure in projecting the front portion of the block through the opening 20 so that the terminals are in position for engaging the prongs of the lamp.

In assembling the parts, the resilient element 11 is inserted through the open top of the casing, followed by the plate 56. The plate is then moved toward the rear wall of the casing to compress the resilient bed so that the base portion of the block 10 may be slid into the open top of the casing. When the lower end of the block has completely entered the casing it will be stopped by the bottom 15 and the finger 39 will project through the notch 21. Upon release of the compressing action, the resilient bed will expand to retain the block in yielding engagement with the flanges 16 and 17 and the ears 23 and 24 will engage over the upper end of the projecting portion 34 to prevent retractive movement of the block.

The sockets assembled as described may be installed in the manner shown in Fig. 3, or the attaching ears 25 and 26 may be bent laterally and secured by any suitable fastening devices, such as screws, rivets, or the like.

In applying the lamp, the prongs at one end are inserted in the tapering portion of the socket terminals at one end of the fixture. Pressure is then applied by the thumb against the finger 39 of the other socket so that the lamp may be swung upwardly with the prongs passing through the slots 41 and 42 to be in position for entering the tapering bores 55 upon release of pressure on the finger 39. When the pressure is relieved, the resilient beds 11 apply sufficient pressure on the blocks so that a positive contact is made between the contact terminals and prong. When it is desired to remove the lamp, pressure is applied to one or the other of the fingers 39 so that the contact elements of the selected socket will disengage from the prongs, after which that end of the lamp may be moved downwardly and outwardly and the prongs at the other end withdrawn from the socket at that end of the lamp.

From the foregoing it is obvious that I have provided a socket tube lamp that is of simple construction and readily assembled. It is also obvious that the lamp is easily applied in the sockets and readily removed therefrom without danger of breaking the parts of the socket or any part of the tube-like lamp.

What I claim and desire to secure by Letters Patent is:

1. A device of the character described including, a casing having a back, sides, and a bottom forming an open front, a body of resilient material in the casing engaging said back, a contact carrying member in the open front of the casing and pressed by the resilient material in the direction of said open front, and contact elements carried by said contact carrying member, said contact carrying member having grooves sloping from an edge thereof in the direction of the contact elements for guiding the prongs of a tube lamp into engagement with the contacting elements.

2. A device of the character described including, a casing having a back, sides, and a bottom forming an open front, a body of resilient material in the casing engaging said back, a contact carrying member in the open front of the casing and pressingly retaining the resilient material against said back of the casing, means on the casing for limiting outward movement of the contact carrying member, contact elements carried by said contact carrying member, said contact carrying member having grooves sloping from an edge thereof in the direction of the contact elements for guiding the prongs of a tube lamp into engagement with the contacting elements, and a thumb piece projecting from the contact carrying member at a point intermediate said grooves to facilitate movement of the contact carrying member into said casing.

3. A device of the character described including, a casing having a back, sides, a bottom, and flanges extending inwardly from said sides, a body of resilient material in the casing, a block-like member in the casing and having side edges engaging said flanges, contact elements carried by said block, and means shifting the block in the casing against said resilient body to fulcrum a portion of the block upon said flanges.

4. A device of the character described including, a casing having a back, sides, a notched bottom, and flanges extending inwardly from said sides, a body of resilient material in the casing, a block-like member in the casing and having side edges engaging said flanges, contact elements carried by said block, and means extending through the notch of said bottom for shifting the block in the casing against said resilient body to fulcrum a portion of the block upon said flanges.

5. A device of the character described including, a casing having a back, sides, flanges on said sides, and a bottom forming an open front, a body of resilient material in the casing engaging said back, a contact carrying member in the open front of the casing and pressed against said flanges by the resilient body, and contact elements including screw-like members having threaded shanks engaged in counterbored openings in said member and having heads engaged in said counterbore of said openings for attaching conductors, said shanks having tapering bores to receive the prongs of a lamp.

6. A device of the character described including, a casing having a back, sides, a bottom, and flanges on said sides and having inwardly extending stops, a body of resilient material in the casing, a block-like member in the casing having side edges engaging said flanges and having a portion engaged under said stops, contact elements carried by said block, and means for fulcruming the block-like member on said stops and against said resilient body.

7. A device of the character described includ-

ing, a casing having a back, sides, and a bottom forming an open front, a body of resilient material in the casing engaging said back, a contact carrying member in the open front of the casing and urged by the resilient material in projecting relation with said open front, contact elements carried by said contact carrying member, said contact carrying member having grooves on the front thereof sloping from an edge thereof in the direction of the contact elements for guiding the prongs of a tube lamp into engagement with the contacting elements and having grooves on the rear thereof to receive conductors connected with said contacts, and an insulating member between said contact carrying member and the resilient material.

8. A device of the character described including, a casing having a front opening, an insulator in the casing, a resilient pad in the casing supporting the insulator over the front opening 20 of the casing and yieldable responsive to pressure applied to the insulator through said opening, contact elements carried by said insulator and having socket portions exposed through said front opening of the casing to receive the prong 25 terminals of a tube lamp, said insulator having fulcruming support on a part of the casing at one side of the front opening, and a lug on the insulator projecting through an opening at the opposite side of the casing whereby said insula- 30

tor is adapted to be engaged and caused to fulcrum on said part of the casing and to move retractively against the yielding pressure of said pad when pressure is applied on said lug.

5 9. A device of the character described including, a casing having a front opening, an insulator in the casing, a resilient pad in the casing supporting the insulator over the front opening of the casing and yieldable responsive to pressure applied to the insulator through said opening, contact elements carried by said insulator and having socket portions exposed through said front opening of the casing to receive the prong terminals of a tube lamp, conductors extending into the casing and having connection with said contact elements, and an insulating member between the insulator and said resilient pad.

10 10. A socket for the contact prongs of a tube lamp including, a casing, a resilient pad in the casing, a contact carrying member in the casing and backed by the resilient pad, contact elements in the carrying member having sockets adapted to receive the prongs of a tube lamp, and means for manually moving said member against said resilient pad to disengage the prongs of a tube lamp, said carrying member having guide grooves spaced according to the spacing of said prongs to guide the prongs into and out of said sockets.

ARTHUR OSTERLOO.
